UNITED STATES PATENT OFFICE

2,549,577

TWO-PIECE ELECTRICAL CONNECTOR

William J. Coyle, Waltham, Mass., assignor to
United-Carr Fastener Corporation, Cambridge,
Mass., a corporation of Massachusetts

Application October 30, 1948, Serial No. 57,523

1 Claim. (Cl. 173—269)

1

The present invention relates to electrical socket contacts such as may be used for the grid connection on an electron discharge tube.

In high voltage radio and electronic circuits, it is known that connections having sharp edges or points cause corona to be formed which are detrimental to the operation of such circuits. One object of my invention is to provide an improved connection having smooth or rounded exterior surfaces which will eliminate corona.

Another object of my invention is the provision of a socket contact of improved construction designed to effect an efficient electrical connection with a cooperating stud part.

A further object of my invention is to provide a socket contact of the above type which may be easily and inexpensively manufactured and assembled.

Other objects of my invention will be apparent from inspection of the drawings and specifications hereinbelow set forth.

Referring to the drawings in which I have illustrated a preferred embodiment of my invention:

Fig. 1 is a fragmentary view of a portion of an electron discharge tube showing one of my improved socket contacts in connection with the grid terminal extending therefrom;

Fig. 2 is a top plan view of the connection shown in Fig. 1;

Fig. 3 is a bottom plan view of the socket contact of Fig. 1;

Fig. 4 is a section taken on line 4—4 of Fig. 3; and

Fig. 5 is an exploded perspective view of the component parts of the socket contact of Fig. 1.

Referring to the drawings, the tube 10, which in the illustrated form, may be an electronic discharge tube, is formed with the usual glass walls having a terminal connector 11 extending from one end thereof. The connector 11 is advantageously in the form of a hollow metal stud member to the interior of which is connected a lead (not shown) of the internal circuit of the tube. The lead is thus in electrical conducting contact with the stud.

The connector 11 is electrically connected to the circuit of the apparatus with which the tube is used, and to carry out this object the socket contact 12 of my present invention is employed. In the illustrated form of my invention the contact 12 is formed of two parts and includes a cup-shaped member 13 and a resilient member 14. In final assembly of the members 13 and 14, the resilient member 14 is disposed within

the cup-shaped member 13 in secured conducting relationship therewith.

The cup-shaped member 13 in the form shown is preferably made of sheet metal in tubular form with a smooth rounded exterior and an integral hemispherical cap at one end. In assembly of the resilient member 14 with the cup-shaped member 13, the edges of the walls of the cup-shaped member 13 are clenched, curled, or rolled inwardly at 15 over the attaching elements of the resilient member 14, as will be more fully described, thereby forming a smooth rounded lower edge. A hole 16 is made or punched in the center of the hemispherical cap. The edges of the cap adjacent the hole are curled or rolled inward to provide a smooth rounded edge.

The resilient member 14 in the form shown is preferably stamped or cut from thin sheet metal and comprises a central body 17 with four resilient leg portions 18 extended angularly from around the peripheral edge of the central body. The legs are formed into resilient contact portions 19 disposed circumferentially around and substantially parallel and spaced from an axis 20 disposed normal to the central body and attaching portions 20 at their outer ends extending angularly outwardly from said axis and said central body.

In order to connect the socket contact to the proper circuit of the radio set or other electronic apparatus, a lead wire 21 which may be covered by insulation is provided which is soldered to the central portion of the resilient member. A small aperture 22 may be provided in said central portion for receiving the wire and aiding in making the soldered connection.

Generally, it is preferable to solder the lead wire 21 to the resilient member 14 prior to assembling it with the cup-shaped member 13. Then, the lead wire 21 is inserted through the bottom of the cup-shaped member 13 and through the aperture 16 in the hemispherical cap portion. The resilient member 14 is then pulled into the cup-shaped member 13 until the central portion is disposed adjacent the curled edges of the aperture 16 in the cap portion and the leg portions 18 are positioned in the tubular portion spaced circumferentially around the interior thereof. The lower edges of the barrel portion are then curled, rolled, or crimped inwards at 15 over the ends of attaching portions 20 of the leg members 18 to retain the resilient member 14 within the cup-shaped member 13.

The other end of the lead 21 may then be soldered or connected to a point of the radio or

electronic circuit as required and this assembled contact 12 applied to the stud or connector 11 on the tube with the contact portions 19 of the leg members 18 resiliently gripping and making an electrical contact at circumferentially spaced points around the contact stud 11.

The provision of the rounded smooth edge at the end of the barrel and at the aperture of the hemispherical cap as well as smooth rounded exterior of the cup-shaped member 13 reduces the tendency for corona discharge to a minimum when the socket member 12 is used, in high voltage electronic or radio circuits.

Although I have illustrated and described a preferred embodiment of my invention, I do not wish to be limited thereby, as the scope of my invention is best defined by the following claim.

I claim:

A contact element including a cup-shaped sheet metal member and a resilient member disposed within said cup-shaped member, said cup-shaped member including a tubular wall portion, a substantially hemispherical shaped end wall portion extending outwardly at one end of said tubular wall portion the terminal end of said end wall portion being curled inwardly and defining a centrally disposed lead wire-receiving opening, an inwardly and reversely curled flange at the other end of said tubular wall portion defining a stud-receiving opening, said flange being spaced inwardly from said tubular wall portion, said re-

silient member including a central body portion disposed adjacent said curved end wall portion of said cup-shaped member and a plurality of leg elements extending from the peripheral edge of said central body portion and spaced circumferentially about the interior of said tubular portion, said leg elements providing contact portions substantially parallel to the axis of said tubular portion for engaging a stud which may be inserted therein and angularly disposed outwardly extending attaching end portions engaged between said curled flange and the interior of said tubular wall portion.
